UNITED STATES PATENT OFFICE

167,261

SMOKING DRAGON ASH TRAY

William Hoffer, New York, N. Y.

Application March 22, 1952, Serial No. 19,016

Term of patent 3½ years

(Cl. D85—2)

To all whom it may concern:

Be it known that William Hoffer, a citizen of the United States of America, residing at New York, in the county of New York and State of New York, has invented a new, original, and ornamental Design for a Smoking Dragon Ash Tray, of which the following is a specification, reference being had to the accompanying drawing, forming part thereof.

I claim:

The ornamental design for a smoking dragon ash tray, as shown.

WILLIAM HOFFER.
